DESIGN FOR A LETTER TRAY SPACER

Frank E. Kebler, Silverton, Ohio, assignor to The
Globe-Wernicke Co., Norwood, Ohio, a corpora-
tion of Ohio

Application November 2, 1945, Serial No. 123,425

Term of patent 14 years

(Cl. D74—1)

To all whom it may concern:

Be it known that I, Frank E. Kebler, a citizen of the United States, and a resident of Silverton, in the county of Hamilton and State of Ohio, have invented a new, original, and ornamental Design for a Letter Tray Spacer, of which the following is a specification, reference being had to the accompanying drawing which forms a part thereof.

In the drawing:

Figure 1 is a plan view of a letter tray spacer showing my new design.

Figure 2 is the corner elevation thereof.

Figure 3 is a front and side elevation thereof.

Figure 4 is a corner elevation of opposite side from Figure 2.

The features which characterize my design for a letter tray spacer consist of the specific config-
urations, the proportions and arrangement of the parts constituting the same, all as illustrated on the drawing.

I claim:

The ornamental design for a letter tray spacer, substantially as shown and described.

FRANK E. KEBLER.
